UNITED STATES PATENT OFFICE.

GEORGE P. THOMAS, OF GLENSHAW, PENNSYLVANIA.

PUNCHING MACHINERY.

1,342,878.

Specification of Letters Patent.

Patented June 8, 1920.

Application filed August 30, 1918. Serial No. 252,070.

To all whom it may concern:

Be it known that I, GEORGE P. THOMAS, residing at Glenshaw, in the county of Allegheny and State of Pennsylvania, a citizen of the United States, have invented or discovered certain new and useful Improvements in Punching Machinery, of which improvements the following is a specification.

My invention relates to machinery for perforating structural steel plates for bridges, buildings, boats, boilers, etc., which machinery includes a punch, plate-supporting tables arranged on each side of the punch, and guides for engaging the opposite ends of a plate for holding it in alinement while it is being advanced and punched.

In operating such machinery, a blank plate is first placed upon the feed table, that is to say the work-supporting table at the feeding side of the punch, and, by working to careful measurements, is manually moved to the proper position for engagement by the guides. After the guides have been attached to the plate they hold it in alinement during the punching operation.

It is well known by those familiar with the operation of such punching machinery that much time is required for centering a plate prior to punching. In point of fact it frequently happens that when punching short plates of different widths almost as much time is required for centering a plate as for punching it. When centering a plate according to the usual practice, the width of each plate must be measured at both ends of the plate (it being understood that a rolled plate may vary considerably in width); the middle point of each end is then marked, and finally the plate is manually moved laterally to the position for proper engagement by the end guides. By way of comment upon the last step, the manual movement of a heavy plate to an exact position is a thing which is not always easy of accomplishment.

With the foregoing considerations in view, it is the object of my invention to provide, for machinery of the character described, means for quickly centering a blank plate upon the feed table prior to the engagement of the plate by the end guides.

In the accompanying sheets of drawings, which form part of my specification, I have illustrated the preferred embodiment of my invention. Figure 1 is a plan view of a

punch and work table; Fig. 2 a side elevation thereof; Fig. 3 a vertical sectional view to enlarged scale taken on the line III—III, Fig. 1; and Fig. 4 a detail sectional view taken on the line IV—IV, Fig. 3.

In the punching machinery which I provide the punch may be of any well known or suitable type. As diagrammatically represented herein, it comprises a frame 1 provided with an anvil 2 and with a reciprocating head 3, which members are in turn respectively provided with usually a plurality of dies 4 and punches 5. The work table also may be of any suitable form or construction, such for example as shown in my Patent No. 835,123. As shown in the drawings, the table comprises supports 6 and 7 arranged on opposite sides of the punch 1 and each provided with narrow work-supporting rolls 8 on which a blank 75 rests while it is being fed through the punch. While both supports 6 and 7 constitute broadly a single work table, the support 6 may be conveniently designated as a feeding table and the support 7 as a receiving table. 80

For feeding a blank and properly controlling the longitudinal spacing intervals, the receiving table 7 may be provided with a guide consisting of a spacing carriage 9, which may be of the general character of 85 that shown in my above mentioned Patent No. 835,123, and the feeding table 6 may be provided with a tail-guide 10, preferably of the character shown in my Patent No. 1,311,539. 90

In the general operation of the punching apparatus as thus far described, a plate to be punched is first placed upon the rolls 8 of the table 6. The plate, after being centered, is attached at its ends to the spacing carriage 9 and the tail-guide 10, and the spacing carriage operated to advance the plate predetermined spacing intervals through the punch between the dies 4 and punches 5. In thus guiding a plate while being punched 100 the carriage or guide 9 rides upon the beams 7 of the receiving table, and the tail guide rides upon a centrally disposed beam 20 of the feeding table.

For centering the plate or other blank 105 upon the table 6, prior to its engagement by the spacing carriage 9 and tail-guide or carriage 10, I provide means for engaging the opposite sides of the blank and moving it laterally toward and to the center line of 110

advance. Such means preferably move simultaneously at the same rate of advance from opposite sides of the table. The means which I show herein for this purpose are particularly illustrated in Fig. 3, and comprise a pair of clamps 11-12 slidably mounted upon arms 13 and 14 projecting laterally from the table 6. An oppositely threaded screw 15 extends transversely of the work table and has threaded engagement with both the clamps 11 and 12, so that by rotating the screw, as by means of a hand wheel 16, both clamps will move simultaneously toward or from the center line of the table, and hence the center line of advance of a plate 17 through the punch. As shown in Figs. 1 and 2, two pairs of such centering clamps are preferably provided, and each pair is preferably movable independently of the other. By thus effecting independently the operation of each pair of clamps, a plate, which may have slight variations in its width, may be properly brought to the desired position for punching.

In the operation of my invention, the two pairs of centering clamps 11 and 12 are, by the rotation of the screws 15, first moved outwardly, and a plate to be punched is placed upon the work-supporting table 6 between such clamps. The hand wheels 16 are then turned independently to rotate the screws 15, and in consequence thereof the pairs of clamps 11, 12 are moved toward the center line of advance of the plate and into engagement with such plate. When the plate has been thus centered its ends are attached to the spacing carriage or guide 9 and the tail-guide 10, the centering means are moved from engagement of the plate, and the end guides coöperate with the table

to hold the plate in proper alinement during the punching operation.

According to the provisions of the patent statutes, I have described the principle and operation of my invention together with the apparatus which I now consider to represent the best embodiment thereof. However, I desire to have it understood that, within the scope of the appended claim, my invention may be practised with other forms of apparatus than that particularly shown and described herein.

I claim as my invention:

The combination of a punch for perforating structural plates, a feeding table on one side and a receiving table on the other side of said punch for supporting a plate while being punched, guides arranged one on each side of the punch and provided with means for engaging the opposite ends of a plate, said guides coöperating with said tables to hold a plate in alinement while being advanced and punched, and plate-centering means arranged on each side of said feeding table and simultaneously moveable uniformly toward and from the center line thereof for engaging the side of a plate resting upon the feeding table and moving such plate into punching alinement prior to the engagement of the plate by said guides, said plate-centering means being removed from engagement of the plate while the plate is being advanced and punched under the control of said guides.

In testimony whereof I have hereunto set my hand.

GEORGE P. THOMAS.
